US0D1101753S

(12) United States Design Patent (10) Patent No.: US D1,101,753 S
(45) Date of Patent:  *Nov. 11, 2025

(54) COVER FOR ELECTRONIC DEVICE

(71) Applicant: SONY INTERACTIVE ENTERTAINMENT INC., Tokyo (JP)

(72) Inventor: Yujin Morisawa, Kanagawa (JP)

(73) Assignee: SONY INTERACTIVE ENTERTAINMENT INC., Tokyo (JP)

(*) Notice: This patent is subject to a terminal disclaimer.

() Term: 15 Years

(21) Appl. No.: 29/917,465

(22) Filed: Nov. 20, 2023

(30) Foreign Application Priority Data

May 31, 2023 (JP) ..... 2023-011079 D

CLAIM

The ornamental design for a cover for electronic device as shown and described.

DESCRIPTION

FIG. 1 is a first perspective view of a cover for electronic device showing my new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a first reference perspective view showing usage state thereof; and,

FIG. 10 is a second reference perspective view showing usage state thereof.

The broken lines depict portions of the cover for electronic device that form no part of the claimed design.

1 Claim, 8 Drawing Sheets
